POWER OUTPUT TUBE BIAS ARRANGEMENT

John S. Starrett, Livingston, N. J., assignor to
Radio Corporation of America, a corporation of
Delaware

Application April 7, 1933, Serial No. 664,969

11 Claims. (Cl. 250—20)

My present arrangement relates generally to circuits for providing bias for power tubes, and more specifically to an improved biasing circuit of this type wherein oscillator voltage is rectified and utilized for providing the bias for the power output tube of a radio receiver.

In using an electron discharge tube as a power output device, it is well known that when a self-biasing resistor is employed, precautions must be taken to prevent undue coupling between the plate and grid circuits. Pulses of current in the plate circuit tend to alter the bias on the grid since the resistor is common to both. To minimize the degeneration and distortion caused by such coupling, a large capacity is usually shunted across the resistor to give this circuit element a time constant sufficiently large so that essentially constant bias is obtained. In larger power tubes (such as the 2A3) where the peak swings of current are large compared to the steady or no signal plate current, and also under class A prime conditions, it is evident that such peaks can be sustained for but a very short interval due to the physical limitations of this network, and hence the maximum power output can be secured only momentarily.

The use of a fixed bias from the bleeder of the receiver would probably result in more satisfactory operation in this respect, but would impose the necessity of providing for quite heavy bleeder currents since the peak current required by the power tubes is large compared to the current required by the other tubes in the receiver. It is, also, apparent that in receivers of the automotive or direct current types where the total supply voltage is limited, the necessity of using part of this for bias limits the power output which may be obtained. In the case of the type 48 tube, two such tubes in push-pull provide an output of about 3.5 watts when used with 95 volts on the plate, while at 125 volts 5.5 watts is obtainable.

From the above considerations it is evident that it would be desirable in many cases to have available an independent source of bias voltage. While this might be obtained from C batteries, the additional space required and other considerations have led receiver designers in the past to look with disfavor upon the inclusion of batteries in an all-electric unit.

Now, I have discovered a novel method of, and devised means for, solving the aforementioned problems. According to the present invention there is provided a method of obtaining a source of bias for the power stage of a receiver which is essentially independent of fluctuations such as

ordinarily experienced when bleeder, or self-biased, circuits are used. The bias is obtained from the rectification of voltages generated within the receiver, whether of beating frequency or not.

It may be stated that it is an important object of my present invention to provide an arrangement for supplying proper negative operating bias for the power output tubes of a radio receiver, as for example of the superheterodyne type, by rectifying a locally generated oscillation voltage, and applying the rectified voltage between the input electrodes of such power tubes.

In applying the present invention to a superheterodyne receiver it has been found convenient and advantageous to embody the local oscillator and rectifier of the beating voltage in a single electrical instrumentality. To accomplish this, advantage has been taken of the fact that there exists an electron discharge tube of the type known as a "duplex diode triode." It may, therefore, be stated that it is another important object of the present invention to provide a superheterodyne receiver with a local oscillator circuit embodying a single tube functioning as a triode oscillator and diode rectifier, the rectifier functioning to rectify the voltage produced by the triode oscillator, and the rectified voltage being applied as a negative bias potential between the input electrodes of the power output tube, or tubes, of the receiver.

Still other objects of the present invention are to improve generally the simplicity and efficiency of superheterodyne receivers, and to provide particularly a receiver of this type which is not only reliable in operation but economically manufactured and assembled.

The novel features which I believe to be characteristic of my invention are set forth in particularity in the appended claims, the invention itself, however, as to both its organization and method of operation will best be understood by reference to the following description taken in connection with the drawing in which I have indicated diagrammatically an arrangement whereby my invention may be carried into effect.

Referring now to the accompanying drawing, wherein the single figure diagrammatically shows a superheterodyne receiver of a conventional type, it will be noted that the first detector tube 1 is of the radio frequency pentode type. In this type of tube the suppressor grid, at cathode potential, is disposed between the positive screen grid and the more positive anode. The source of positive potential for the screen grid of tube 1

is designated by the symbol S_1 , and the source of the more positive potential for the anode of tube 1 is designated by the symbol P_1 . A negative bias is supplied to the control electrode of tube 1 from 5 a source G (not shown), the negative terminal of this source being connected to the control electrode of tube 1 through a path which includes the resistor R_1 , and the coil L_1 .

Signal energy is impressed upon the tunable 10 input circuit of tube 1 through the coupling transformer M_1 , and the variable tuning condenser C_4 is connected in the usual manner across the coil L_1 . The grounded side of the condenser C_4 is connected to the low potential side of the coil L_1 15 through a direct current blocking condenser C_7 .

The anode circuit of the tube 1 includes therein 20 a coil L_5 shunted by a fixed condenser C_8 . The high potential side of the network L_5-C_8 is connected to ground through a radio frequency by-pass condenser 2. The network L_5-C_8 is maintained 25 fixedly resonant to the operating intermediate frequency, and the intermediate frequency energy derived from this network is impressed upon a succeeding intermediate frequency amplifier. This amplifier is omitted since its construction is well known to those skilled in the art. Additionally, the second detector which usually follows such an amplifier is omitted, and in order to preserve simplicity of description, 30 there is only shown the input transformer connected to the power output tubes 3, 4.

The audio frequency input transformer M_1 has its primary coil L_6 arranged for connection to the 35 output circuit of the second detector, while the secondary coil L_7 has one side thereof connected to the control electrode of tube 3, and its other side connected to the control electrode of tube 4. Both cathodes of tubes 3 and 4 are grounded. The anode of tube 3 is connected to one side of 40 the output transformer primary coil L_8 , while the anode of tube 4 is connected to the opposite side of this coil. The secondary coil of the power output transformer is arranged for connection to a reproducer, not shown, or it may even be 45 connected to additional stages of audio frequency amplification.

The anodes of tubes 3 and 4 are energized from 50 a source of positive potential P_2 , not shown, and the lead from the positive terminal of this source to the anodes of tubes 3 and 4 is connected to the midpoint of the coil L_8 . The midpoint of the coil L_7 is connected by a lead 5 to a negative biasing arrangement to be hereinafter described.

The local oscillator circuit of the superheterodyne receiver shown comprises the tube 6, this tube being of the duplex diode triode type described and claimed by Terry M. Shrader in application Serial No. 622,140, filed July 12, 1932. It is not believed necessary to go into details with 55 regard to the description of this type of tube since the aforementioned Shrader application describes the construction in detail. It is believed sufficient to point out that the tube 6, which may be of the 55 or 85 type, is a tube consisting of two diodes and a triode in a single envelope. The two diodes and the triode are independent of each other, except for a common cathode sleeve 7 which has one emitting surface for the diodes and another for the triode.

Within the common envelope of the tube are 70 provided the auxiliary diode anodes 8 and 8', while the triode portion of the tube comprises the main anode 9 and the usual control grid 10 disposed between the cathode 7 and the anode 9.

The two diode plates 8 and 8' are placed around a portion of the emitting surface of the cathode 7 which is independent of the portion of the emitting surface around which the grid 10 and anode 9 are disposed. In other words, the diode anodes 8 and 8' are outside the electron stream passing through the grid 10 to the anode 9.

The triode portion of the tube 6 is utilized as the local oscillator of the receiver, while the diode portion of the tube is used as the rectifier for the oscillator beating voltage, the rectified voltage to be utilized as the negative biasing voltage for the power output tubes. The coil L_4 is shown coupled to the conventional oscillator coil assembly and rectified current flows in the resistor R_1 . The conventional oscillator coil assembly 15 comprises the feed-back coil L_3 , connected between the anode 9 and the positive terminal of the anode potential source P_3 (not shown).

A radio frequency by-pass condenser 11 is connected between ground and one side of the feed-back coil L_3 . The coil L_2 is disposed in the circuit of the cathode of the first detector tube 1, the grounded side of the coil L_2 including a resistor R_2 shunted by a radio frequency by-pass condenser 12.

Both coils L_3 and L_2 are coupled to each other and to the coil L_1 , the latter coil being connected, on one side thereof, to the grid 10 through the condenser C_6 , there being shunted across the coil L_1 a fixed condenser C_2 and the variable condenser C_3 . A lead 13 is connected between a point intermediate condensers C_2 and C_3 and the grounded side of the cathode 7, and the resistor R_3 is connected between the grid 10 and grounded side of cathode 7. The bias resistor R has one side thereof connected to the grounded side of the cathode 7 and its other side connected to the lead 5.

The coil L_4 has one side thereof connected to the diode anodes 8 and 8', the both anodes being tied together, while the opposite side of the coil is connected, through a lead 14, to ground through a condenser C_1 , a radio frequency by-pass condenser C being connected between the grounded side of resistor R and the anode side of condenser C_1 . The variable condensers C_4 and C_5 preferably have their rotors mechanically coupled for simultaneous adjustment in any well known manner, and this is designated by the dotted line 15. The condenser C is a by-pass for the beating frequency, while the condenser C_1 serves to keep this voltage from the power tube grids. The resistor R should be sufficiently large so that no appreciable load is put on the oscillator. The power tube grids are connected to the negative end of the resistor R .

The signal input network preceding the first detector tube 1 may include one or more tuned radio-frequency amplifier stages, if desired. Also, all the electrode direct current operating potentials may be derived from a common source, such as the filtered rectified output from an alternating current source, such arrangements being well known to those skilled in the art. The operation of the circuit described above will be clearly understood from the following explanation:

The locally produced oscillations are impressed upon the cathode circuit of the first detector, or frequency changer tube, and the local oscillations are, of course, produced by feeding radio frequency energy from the anode circuit of tube 6, through coils L_3 and L_1 , to the grid circuit thereof. In other words, the triode portion 7, 10 and 9

of tube 6, and its associated coils L₃ and L₄, function as a triode oscillator. The two diode anodes 8 and 8' tied together, and their associated cathode emitting surface, function as a diode rectifier, the radio frequency energy to be rectified being derived by means of the coil L₄ from the local oscillator group of coils. The rectified energy across the resistor R is employed as the negative biasing voltage for the grids of the power 10 output tubes 3 and 4.

C₆ is a grid condenser of say .00025 microfarad capacity and works in conjunction with R₃ as the grid leak condenser combination commonly used when no applied bias is used on an oscillator.

C₂ is part of the tank circuit, or tuning capacity. The negative biasing voltage obtained from the oscillator would vary considerably with frequency if the ordinary coil and condenser connections were used. The combination of C₂ and C₃ indi-

cates a means of keeping this voltage constant. The cathode is connected to a variable potential point between these condensers. When C₃ is varied from maximum to minimum capacity the normal increase in voltage with increase in fre-

25 frequency is reduced due to the increased impedance of C₃ as compared to C₂. Thus by proper proportioning of C₂ and C₃ quite constant voltage will be introduced into coil L₄. Other networks of capacity and inductance might be employed in

30 place of that shown to secure the constant voltage condition.

An alternative arrangement to accomplish the aforementioned result would be to employ an extra winding on the power transformer of the receiver, with a small rectifier tube connected to rectify the 60 cycle alternating current voltage. With such a circuit however the filter would need to be very effective because of the possibility of introducing hum, and would be relatively more 40 expensive and bulky, than the filter required for radio frequencies. An extra tube would also be required if 60 cycles were used, while in the radio frequency energy only the usual number of tubes is needed.

45 While I have indicated and described one system for carrying my invention into effect, it will be apparent to one skilled in the art that my invention is by no means limited to the particular organizations shown and described, but that 50 many modifications may be made without departing from the scope of my invention as set forth in the appended claims. For example, the invention is applicable to a combined detector-oscillator, that is an autodyne first detector circuit, instead of independent oscillator and detector tube 55 circuits.

What I claim is:

1. A method of biasing an input electrode of a power output tube of a radio receiver which includes the steps of detecting signal energy for subsequent amplification by said power tube, simultaneously producing local oscillation energy of a frequency of the order of the signal frequency, rectifying said oscillation energy, and applying said rectified energy as a biasing potential for said input electrode.

2. In a superheterodyne receiver, provided with a first detector and at least one audio frequency amplifier tube, and a local oscillator circuit, a rectifier network operatively associated with said local oscillator for rectifying the oscillator beating voltage, and means for applying said rectified voltage to an input electrode of said amplifier tube 75 as a bias therefor.

3. In a superheterodyne receiver, provided with a first detector and at least one audio frequency amplifier tube, and a local oscillator circuit, a diode rectifier network operatively associated with said local oscillator for rectifying the oscillator beating voltage, and means for applying said rectified voltage to an input electrode of said amplifier tube as a bias therefor.

4. In a superheterodyne receiver, provided with a first detector and at least one audio frequency amplifier tube, and a local oscillator circuit, means for tuning the oscillator circuit over a frequency range, a rectifier network operatively associated with said local oscillator for rectifying the oscillator beating voltage, means in the oscillator circuit to maintain the rectified voltage constant, and means for applying said rectified voltage to the grid of said amplifier tube as a bias therefor.

5. In combination with a superheterodyne receiver of the type including a frequency changer network, a succeeding audio frequency amplifier tube, and a local oscillator circuit, a diode rectifier circuit coupled to said local oscillator circuit to derive oscillator energy therefrom, said rectifier circuit including an impedance for developing a direct current potential, and a conductive connection between the negative side of said impedance and an input electrode of said amplifier tube.

6. In combination with a superheterodyne receiver of the type including a frequency changer network, a succeeding audio frequency amplifier tube, and a local oscillator circuit, a diode rectifier circuit coupled to said local oscillator circuit to derive oscillator energy therefrom, said rectifier circuit including an impedance for developing a direct current potential, and a conductive connection between the negative side of said impedance and an input electrode of said amplifier tube for impressing said potential on the said electrode, said local oscillator circuit and diode rectifier circuit having their electrodes disposed within a common tube envelope.

7. In combination with a superheterodyne receiver of the type including a frequency changer network, a succeeding audio frequency amplifier tube, and a local oscillator circuit, a diode rectifier circuit coupled to said local oscillator circuit to derive oscillator energy therefrom, said rectifier circuit including an impedance for developing a direct current potential, and a conductive connection between the negative side of said impedance and an input electrode of said amplifier tube for impressing said potential on the said electrode, said local oscillator and diode rectifier circuits having their electrodes disposed within a common tube envelope, the cathode of said common tube being common to the oscillator and rectifier electrodes.

8. In combination with a superheterodyne receiver of the type including a frequency changer network, a succeeding audio frequency amplifier tube, and a local oscillator circuit, a diode rectifier circuit coupled to said local oscillator circuit to derive oscillator energy therefrom, said rectifier circuit including an impedance for developing a direct current potential, and a conductive connection between the negative side of said impedance and an input electrode of said amplifier tube for impressing said potential on the said electrode, said local oscillator and diode rectifier circuits having their electrodes disposed within a common tube envelope, the cathode of said common tube being common to the oscillator and rectifier electrodes.

rectifier electrodes and the diode anode being disposed outside the electron stream to the oscillator anode.

9. An audio frequency amplifier stage including a pair of tubes connected in push pull, an oscillator circuit comprising a tube provided with independent triode and diode sections, circuits associated with said triode section for providing a triode oscillator circuit, circuits associated with said diode section, said diode circuits being coupled with said oscillator circuits, providing a diode rectifier circuit for the locally produced oscillation energy, and a conductive connection for applying the rectified energy as a negative bias for the grids of said push pull connected tubes.

10. In combination with a superheterodyne receiver of the type including a frequency changer network, a succeeding audio frequency amplifier tube, and a local oscillator circuit, a diode rectifier circuit coupled to said local oscillator circuit to derive oscillator energy therefrom, said rectifier circuit including an impedance for developing a direct current potential, a conductive connection between the negative side of said impedance and an input electrode of said amplifier tube, means for tuning the frequency changer network through a desired signal frequency range, means for tuning the local oscillator circuit through a

range of frequencies differing from the signal frequencies by the operating intermediate frequency, and additional means in the local oscillator circuit for maintaining the said direct current potential constant in value as the oscillator tuning means is varied.

11. In combination with a superheterodyne receiver of the type including a frequency changer network, a succeeding audio frequency amplifier tube, and a local oscillator circuit, a diode rectifier circuit coupled to said local oscillator circuit to derive oscillator energy therefrom, said rectifier circuit including an impedance for developing a direct current potential, and a conductive connection between the negative side of said impedance and an input electrode of said amplifier tube, said local oscillator circuit and diode rectifier circuit having their electrodes disposed within a common tube envelope, means for tuning the frequency changer network through a desired signal frequency range, means for tuning the local oscillator circuit through a range of frequencies differing from the signal frequencies by the operating intermediate frequency, and additional means in the local oscillator circuit for maintaining the said direct current potential constant in value as the oscillator tuning means is varied.

JOHN S. STARRETT.
